UNITED STATES PATENT OFFICE.

PIETRO IACOVINO, OF NEW YORK, N. Y.

ARCH SUPPORTER.

Application filed March 21, 1925. Serial No. 17,411.

This invention relates to footwear and particularly to an improved arch supporter and has for an object to provide a construction which may be readily applied to foot-
5 wear during the course of manufacture or after the manufacturing operation has been completed and function properly for supporting the arch and tilting the foot in the desired manner.

10 Another object of the invention is to provide an improved supporter wherein a stiffening metallic strip is provided immediately below the arch and a resilient pad at a forward point for tilting the foot to overcome
15 any defects therein.

A still further object of the invention is to provide an insert for shoes wherein means are provided for holding the insert in place and means holding part of the insert are
20 arranged to cause the foot to take the right position in the shoe.

In the accompanying drawing—

Figure 1 is a fragmentary longitudinal vertical sectional view through a shoe with 25 an embodiment of the invention applied thereto.

Figure 2 is a bottom plan view of the supporter shown in Figure 1, the same being on a greatly enlarged scale.

30 Figure 3 is a sectional view through Figure 1, approximately on line 3—3.

Referring to the accompanying drawing by numerals, 1 indicates a piece of footwear of any kind, as for instance, an ordinary shoe and 2 the insert. The insert 2 is preferably formed from a piece of leather 3 cut a desired shape as shown in Figure 2, a metal bracing or stiffening member 4 and a pad 5 preferably of rubber. The stiffening 35 and supporting member 4 is permanently arc-shaped and is connected with the leather body 3 by rivets 6 and 7. The respective ends of the metal supporter 4 are formed with spurs 8, which spurs are forced into the inner sole 9 of the shoe 1. Usually the spurs are made of sufficient length to not only pass through the inner sole but pass for a short distance into the outer sole and in this manner firmly anchor the supporter 2 in position so that the supporter when correctly placed in the shoe is held there and the same is prevented from slewing or slipping side-

wise. At any desired place between the arch and the toe is arranged a pad 5 cemented or otherwise secured to the body 3 and formed with a thickened portion tapering to a thin edge in three directions whereby a raised section is provided while the body 3 covering the pad 4 presents a smooth continuous surface. Preferably the edge 10 is chamfered or beveled for an appreciable distance back whereby there will be no abrupt change from the top surface of the body 3 and the top surface of the front part of the inner sole 9. The pad 5 has been shown on the left side of the right foot so as to support the right foot near the great toe. The pad is positioned at this point in order to take care of any improper shape or zagging of the foot at the point indicated and thereby prevent twisting of the foot when inserted into the shoe. If the right side of the right foot should be lower than normal, a suitably shaped pad would be used on the body 3 below the right side to support the right side of the foot in order that there will be no twisting of the foot when the pressure of the body is brought to bear thereon. It will be understood that the left foot may have a supporter embodying the invention and the pad 5 adjusted to the particular condition or shape of the foot.

What I claim is:

In an arch supporter, a leather body adapted to fit flatwise into the bottom of a shoe and extend across the shank of the shoe, a rectangular straight narrow metallic stiffening member curved longitudinally, said stiffening member being formed with struck-out portions at each end in alignment with the longitudinal center of the stiffening member and presenting spurs adapted to be forced into the sole portion of the shoe and preventing slewing of the supporter, rivets positioned back from the ends of said stiffening member for rigidly connecting the stiffening member with the leather body and leaving the spurred ends free, and a pad near the forward end of the said leather body for tilting the forward end of the said leather body for tilting the forward inner part of the foot when the supporter is in use.

PIETRO IACOVINO.
